UNITED STATES PATENT OFFICE.

MAX DRUCKERMAN, OF BROOKLYN, NEW YORK.

CIRCULAR EMBROIDERY-SEAM.

1,083,602.

Specification of Letters Patent.

Patented Jan. 6, 1914.

Application filed March 7, 1913. Serial No. 752,576.

To all whom it may concern:

Be it known that I, MAX DRUCKERMAN, a citizen of the United States, and a resident of Brooklyn, in the county of Kings and State of New York, have invented certain new and useful Improvements in Circular Embroidery-Seams, of which the following is a specification, taken in connection with the accompanying drawing, which forms a part of the same.

My invention relates to the art of embroidery, wherein I form a circular embroidery seam of two or more needle threads, a single shuttle thread coöperating with the needle thread and a filler to raise any suitable portion of the fabric, which filler is preferably held in place by the threads of the seam.

More particularly my invention is employed to represent flowers or other articles, which can be shaded by varying the colors of the needle threads, and portions of the embroidery unit may be raised in relief, though it is to be understood that all the needle threads may be white or any other color.

My circular embroidery seam is used alone or in combination with other similar embroidery units, or different embroidery units, to represent in machine embroidery, flowers or other articles.

In the accompanying drawing, showing illustrative embodiments of my invention, and in which the same reference numerals refer to similar parts in the several figures,—Figure 1 is a fragmentary plan view of a piece of fabric embroidered with different forms of my circular embroidery seam shown as flowers upon a twig; Fig. 2 is a

diagrammatic fragmentary plan view of the obverse of the simplest form of my present invention showing two needle threads, one shuttle thread and a filler for raising the fabric upon the obverse between the different sets of needle threads; Fig. 3 is a fragmentary diagrammatic view of the obverse of a modified form of my circular seam showing three needle threads, one shuttle thread and a filler; Fig. 4 is a fragmentary

diagrammatic plan view of the reverse of the embroidery unit shown in Fig. 3; and Fig. 5 is a transverse vertical section substantially on the line 5—5 of Fig. 3.

In the illustrative embodiments of my invention shown in the drawings, 1 is a piece

of material of any description through which the needles (not shown) of the sewing machine will thread the needle threads. Usually this material is some suitable fabric but, of course, it is to be understood that my invention is not to be limited to such material. On this fabric 1 is embroidered a twig 2 having flowers 3, 4 and 5. It must be understood that if these flowers are truly represented to show all the needle threads of which they are formed, these pieces of embroidery 3, 4 and 5 would have to be shown as substantially solid black rings.

The simplest form of my present invention comprises a circular embroidery seam, Fig. 2, having two needle threads 6 and 7 and one shuttle thread or locking thread 8, the latter, of course, appearing on the reverse and is indicated in dotted lines in this Fig. 2. These needle threads 6 and 7 are preferably so positioned as to leave an appreciable interval 9 between them upon the face or obverse of the material. To imitate certain articles and particularly flowers, it is desirable to bring out in relief some portion of the circular embroidery seam. I have shown for convenience the fabric on the obverse being raised or brought into relief by a filler 10 of any suitable description, as for example a cord, which I have shown for illustration mounted on the reverse substantially between the different sets of needle threads 6 and 7 which appear on the face or obverse. I also preferably though not necessarily employ a binding cord 11 around the opening 12 in the fabric 1, this cord serving to raise the embroidery around the edge of the opening 12 as well as to give the embroidery body at that point.

The first needle (not shown) lays down its needle thread 6 upon the obverse of the fabric 1 until it reaches the point 13 when the needle thread 6 is threaded through the fabric forming on the reverse the needle thread loops 14 through which passes the shuttle thread 8. It again emerges at the point 15 and lays down its thread on the obverse and over the cord 11, if one is used, and then passes on the reverse forming the loops 16, back of the filler 10, and coöperating with the shuttle thread 8; and so on throughout its travel, it, of course, being understood that the needle threads 6, 6 if truly represented would be simply a black ring. The second needle thread 7 at the same time is

laid down upon the obverse of the fabric 1 by a second needle (not shown) starting for example at the point 17 and thence to the periphery 18 of the embroidery unit, where it is threaded through the fabric by the second needle (not shown) forming the secondary needle thread loops 19 which are caught by the same locking or shuttle thread 8, thence back to the periphery of the embroidery seam where the secondary needle thread is again laid down on the fabric until it reaches a point, as for example, 20, when the secondary needle will thread it through the fabric forming the secondary needle loops 21 which in turn are caught by the same shuttle threads 8; and so on as indicated by the drawings until the completed piece of embroidery has been formed, it, of course, being understood that in commercial practice this embroidery is made by the machine much quicker than it can be described, both needles operating simultaneously in the well known ziz zag manner. The loops of the primary and secondary needle threads upon the reverse of the fabric 1 pass on the rear of the cord or filler 10 and serve to hold it in its proper position.

By varying the color of the needle threads 6 and 7, and also the thickness of the filler 10, various effects in imitation of flowers, or other articles, may be obtained. If the fabric 1 is white and the needle threads 6 and 7 colored, for example, a circular embroidery seam is obtained having two rings of needle threads and a raised intermediate portion of white. By having the needle threads 6 or 7 white and the fabric 1 colored, or by varying the shades of the needle threads 6 and 7, either having the fabric white or some shade to harmonize with the shade of the needle threads the most beautiful effects in embroidery can be obtained.

In Figs. 3, 4 and 5 I have shown my embroidery formed with three different and independent radial needle threads 23, 24 and 25, each needle thread having its own needle (not shown) and all three needle threads coöperating with the one shuttle or locking thread 26. I have arranged the radial needle threads 23 adjacent to the opening 27 in the fabric, then left a portion 28 of the fabric 29 uncovered before laying down the second needle thread 24, the third set of threads 25 are at the circumference of the embroidery unit and preferably spaced from the second needle threads 24 leaving a slight uncovered portion 31 of the fabric 29.

Under the uncovered portion 28, for example, I preferably mount a filler 32 of cord or any other suitable material. I also preferably form a cord or filler 33 around the edge of the opening 27, though, of course, this second filler may be omitted, if desired. The stitches in this form are made

the same as in the simpler form shown in Fig. 2 except that there is an additional needle and an additional needle thread.

Taking for example the needle thread 23 which is governed by the first needle, it is laid down on the obverse until it reaches the point 34, when it is threaded through the fabric or material 29 and forms the loops 35 on the reverse which loops coöperate with the shuttle or locking thread 26. It is then brought out at the point 36 and is again laid down on the obverse of the fabric passing over and around the cord 33, if one is used, and then forming on the reverse the loops 37 around the shuttle thread 26 and back again to the opening 27, this movement being repeated in an obvious manner to make the complete inner ring formed by the primary or first needle thread 23. In passing back of the filler 32, it serves to hold the filler in its proper position and, of course, at the same time that portion 28 of the fabric 29 will be raised.

The second needle (not shown) enters the goods, for example, at the point 38, then lays down the second needle thread 24 until it reaches the point 39 when the second needle will thread it through the material 29 and form the loops 40 to coöperate with the same shuttle thread 26, the secondary needle thread 24 being then brought back to the point 41 and laid down on the face or obverse until it reaches the point 42 when it is again threaded through the fabric to form the loops 43 to coöperate with the same shuttle thread 26; and so on until the complete ring formed by the second needle thread 24 is made, all the loops coöperating with the same shuttle thread 26. At the same time that the first and second needles are traveling in a zig zag manner to lay down the needle threads 23 and 24, the third needle (not shown) is simultaneously in the same manner laying down the third needle thread 25 entering the cloth at the point 45 and laying down that needle thread on the obverse of the fabric 29 until the point 46 is reached on the circumference of the circular unit of embroidery. The third needle (not shown) will then thread the third needle thread 25 through the fabric 29 to form the needle thread loops 47 which are locked by the same shuttle or locking thread 26. The third needle then brings its needle thread to a point 48 whence the third needle thread is brought back through the fabric, from the reverse to the obverse, and is again laid down upon the fabric until the point 49 is reached when the thread is then threaded through the fabric to form the loops 50 which also coöperate with the same shuttle or locking thread 26; the thread being then brought back to the point 51 and out onto the face of the embroidery unit when the third needle thread is again laid

down until it reaches the point 52; and so on until the complete piece of embroidery is made, each needle proceeding in a zig zag manner simultaneously and all the needle threads coöperating with the one shuttle thread. By this form of my invention beautiful pieces of embroidery may be obtained by varying the color of the needle threads 23, 24 and 25 either to obtain striking contrasts or having them of different shades of the same color, so that the piece of embroidery which, for example, we will assume is an imitation of a flower, can be shaded either from the center out to its circumference, or from its circumference in to its center, whichever may be the proper shading for the particular thing imitated. The filling raises a portion of the goods which serves to beautify the embroidery. The proper shades and colors are used to imitate any particular flower or article which may be desired, it, of course, being understood that the position of the filling may be varied as found convenient or expedient.

Having thus described this invention in connection with illustrative embodiments thereof to the details of which I do not desire to be limited, what is claimed as new and what it is desired to secure by Letters Patent is set forth in the appended claims:

1. An article of manufacture comprising a piece of material having a circular embroidery seam formed of two or more independent radial needle threads each having radial needle thread loops located at different distances from the center of the embroidery, a single shuttle thread coöperating with the different radial needle thread loops, and a filler secured to the material by two or more independent needle thread loops and the single shuttle thread.
2. An article of manufacture comprising a piece of material having a circular embroidery seam formed of two or more independent radial needle threads each having radial needle thread loops located at different distances from the center of the embroidery, a single shuttle thread coöperating with the different radial needle thread loops, and a filler secured to the material by two or more independent needle thread loops and the single shuttle thread.
